PICTURE FRAME

Gregorio Mauricio Austria, San Francisco, Calif.

Application January 18, 1954, Serial No. 28,555

Term of patent 14 years

(Cl. D29—20)

Fig. 2

To all whom it may concern:

Be it known that I, Gregorio Mauricio Austria, a citizen of the United States of America, resident of San Francisco, California, have invented a new, original, and ornamental Design for a Picture Frame, of which the following is a specification, reference being made to the accompanying drawing, forming a part thereof.

Fig. 1 is a front elevational view of a picture frame showing my new design; and

Fig. 2 is a sectional view thereof taken along the line 2—2 of Fig. 1.

I claim:

The ornamental design for a picture frame, substantially as shown.
